UNITED STATES PATENT OFFICE.

IVY McTIMMONDS, OF MITCHELL, OREGON.

BED.

1,229,168.

Specification of Letters Patent.

Patented June 5, 1917.

Application filed June 9, 1916. Serial No. 102,732.

To all whom it may concern:

Be it known that I, Ivy McTimmonds, a resident of Mitchell, Wheeler county, Oregon, and a native-born citizen of the United States, have invented new and useful Improvements in Beds, of which the following is a specification.

This invention relates to improvements in beds and especially with reference to the provision of a foldable bed spring or bed bottom, which may be widened or narrowed at will and used either on a double or single bedstead and also with reference to the provision of a bedstead of novel construction which may be widened for use as a double bed or narrowed for use as a single bed at will.

The invention consists in the features of construction, combination, and arrangement of devices, hereinafter fully described and claimed.

In the accompanying drawings:

Figure 1 is a perspective view of a bed bottom or spring, constructed and arranged in accordance with my invention and showing the same extended for use as a double bed.

Fig. 2 is a transverse sectional view of the same in folded position, for use as a single bed.

Fig. 3 is a detail longitudinal sectional view of the same.

Fig. 4 is an elevation, partly in section of the bedstead.

Fig. 5 is partly an end elevation and partly a transverse sectional view of the same, in widened position in full lines and narrowed as for use as a single bed in dotted lines.

Figs. 6 and 7 are detail views.

The bed bottom or spring 1 comprises a pair of end members 2 which are preferably channel irons. Each end member has sections 3, 4, which are arranged end to end and are pivotally or hingedly connected together at their upper sides as at 5, so that the sections 4 may be extended from the sections 3 to form a double bed, or may be folded over and upon the sections 3 to form a single bed, as will be understood. The outer ends of the sections 3 of the end members are connected together by a bar 6. The lower web 7 of each section 4 is provided with a longitudinal slot 8. A rod 9 connects the sections 4 together and has its ends 10 turned

at right angles, and slidably engaged in the slots so that said rod may be moved to the outer ends of the sections 4 when the bed is extended for use as a double bed and so that when the sections 4 are folded over the sections 3 to arrange the bed for use as a single bed, the rod 9 will drop to the inner ends of the slots 8 and will be arranged at the side of the bed opposite the rod 6. The sections 3, 4, are provided at their outer ends with downwardly extending and outwardly projected studs 11 for engagement in the socket brackets of the bedstead, and to secure the bed bottom or spring and its frame between the head and foot members of the bedstead. A spring fabric 12 of any suitable construction is attached to and stretched between the end members 2. Each section 3 is also provided at its inner end on its under side with a downwardly extending stud 13.

The head 14 and foot 15 of the bedstead, each comprise a pair of slidably related members 16, 17. The member 16 is provided with a pair of posts 18. The member 17 has a single post 19 at its outer side. The member 16 has parallel spaced cross bars 20 which are here shown as dove-tailed channel bars, and the member 17 has corresponding cross bars 21, each of which is provided on its inner side with a dove-tailed tongue 22 slidably fitted in the dove-tailed groove formed by one of the bars 20. Hence the members of the head and foot of the bed are slidably connected and may be extended to adapt the bed for use as a double bed or the member 17 may be moved inwardly to arrange their posts 19 in line with two of the posts of the members 16 and thereby narrow the bed and enable it to be arranged for use as a single bed. The members 16, 17 are provided with socket brackets 23 for the reception of the studs 11 of the bed bottom or frame, when the bed is arranged for use as a double bed and each member 16 also has a socket bracket 24 for the reception of the stud 13 and to support the corresponding end of the bed bottom section 3. These brackets 23 are offset to allow complete telescoping to the members of the bed.

To lock the members 16, 17 together, when the bed is arranged as a single bed, the section 16 is provided in its upper side with a vertical opening 25 on each side and the section 17 is provided at its upper side with an arm 26 which extends inwardly above the

section 17 and carries a vertically movable bolt 27 which may be dropped into or drawn from either of the openings 25.

Having described the invention, what is claimed is:

- 5 1. A bed bottom or spring comprising end members, each consisting of a pair of hingedly connected sections, so that one of said sections may be folded on the other, and a bar connecting the outer ends of each of the sections, and a third bar slidably connected to one pair of the sections so that the third bar may be arranged at one side of the bottom or spring, both when the same is in extended and in folded position.
- 10 2. A bed bottom or spring comprising channeled end members, each consisting of
- 15

a pair of hingedly connected sections so that one of said sections may be folded on the other, the lower webs of one section of one end member and of the corresponding section of the other end member being each provided with a longitudinal slot, side bars connecting the outer ends of said sections and a third bar having down turned ends slidably engaged in said slots, said third bar being thus arranged for slidable movement on said slotted sections.

In testimony whereof I affix my signature.

IVY McTIMMONDS.
